(57) **CLAIM**

The ornamental design for a container for lubricants, as shown and described.

DESCRIPTION

FIG. 1 is a front elevational view of a container for lubricants showing our new design;

FIG. 2 is a front, right, and top perspective view thereof;

FIG. 3 is a top plan view thereof;

FIG. 4 is a bottom plan view thereof;

FIG. 5 is a left side elevational view thereof; and,

FIG. 6 is a right side elevational view thereof.

The broken lines in the drawings depict portions of the container for lubricants that form no part of the claimed design.
